US0D1080238S

(12) United States Design Patent (10) Patent No.: US D1,080,238 S
(45) Date of Patent:  Jun. 24, 2025

(54) SOFA

(71) Applicant: Anji Longwin Furniture Co., Ltd.,
Huzhou (CN)

(72) Inventors: Chen Ding, Huzhou (CN); Hu Zhou,
Huzhou (CN); Xuezhong He, Huzhou
(CN); Zhongjian Huang, Huzhou (CN)

(73) Assignee: Anji Longwin Furniture Co., Ltd.,
Huzhou (CN)

() Term: 15 Years

(21) Appl. No.: 29/922,742

(22) Filed: Dec. 26, 2023

(30) Foreign Application Priority Data

Nov. 29, 2023 (CN) 202330785070.2

(51) LOC (15) Cl. 06-01

(52) U.S. Cl.

USPC D6/361; D6/381

(58) Field of Classification Search

USPC D6/334–336, 360, 361, 371, 373, 374,

D6/375, 377, 381, 382; D5/47, 53

CPC A47C 1/02; A47C 17/00; A47C 17/002;

D03D 5/56
